METHOD OF MINING COAL

Edmund C. Morgan, deceased, late of New York,
N. Y., by Olive Eugenie Morgan, executrix, New
York, N. Y., assignor to American Morgan
Company, a corporation of Delaware

Original application June 23, 1913, Serial No.
775,173. Divided and this application April 25,
1932, Serial No. 607,344

9 Claims. (Cl. 262—1)

This application is a division of the co-pending application Serial No. 775,173, filed June 23, 1913.

This invention relates to apparatus for mining coal or other materials, and more particularly to such as are characterized by the cutting of a plurality of kerfs for the purpose of enabling the coal or other materials to be removed in blocks of substantially regular and uniform masses, but it should be understood that the invention may have a general application in cutting coal or other material.

One of the objects of the invention is to generally improve and simplify apparatus for mining coal or other materials and to increase the flexibility of operations by enabling a single kerf-cutter to perform a variety of operations without changing the structure of the machine.

Other objects of the invention will appear hereinafter, the novel features and combinations being set forth in the appended claims.

Referring to the accompanying drawings:

Fig. 1 is a general view in side elevation of a mining machine embodying the present invention;

Fig. 1^a represents a fragmentary view, partly in elevation and partly in central vertical section, of Fig. 1, to show the pivotal connection between the turn-table and the truck;

Fig. 2 is a general top plan view of the machine shown in Fig. 1;

Fig. 2^a is a plan view of a portion of Fig. 2 to show the power transmission between the motor and the main frame and the advancing and retracting beam;

Fig. 3 is an enlarged elevation view of a cutting mechanism or cutter bar embodying the present invention;

Fig. 3^a is a transverse sectional view of the cutting mechanism on the line 3^a—3^a of Fig. 3;

Fig. 4 is a rear end elevation of the machine shown in Figs. 1 and 2;

Fig. 5 is an enlarged sectional view on the line 5—5 of Fig. 6, of the mechanism for transmitting power to the cutting mechanism and for actuating the cutting mechanism;

Fig. 6 is a longitudinal sectional view on the line 6—6 of Fig. 5;

Fig. 7 is an enlarged detail view of the mechanism for retaining the control levers in their various positions;

Fig. 8 is a fragmentary view in side elevation similar to the corresponding portion of the structure shown in Fig. 1, but illustrating a modified construction.

Fig. 9 is a top plan view of the mechanism shown in Fig. 8;

Fig. 10 is a sectional view on the line 10—10 of Fig. 1, similar to Fig. 5 but showing the details of the modified construction illustrated in Figs. 8 and 9;

Fig. 11 is a longitudinal sectional view on the line 11—11 of Fig. 10;

Figs. 12 and 13 are diagrammatic views illustrating a method of mining coal;

Fig. 14 is a diagrammatic view illustrating the manner in which the present mining machine may be employed for cutting kerfs in the coal;

Fig. 15 is a view similar to Fig. 14 showing the horizontal or vertical kerf cut by the present machine;

Fig. 16 is a diagrammatic view in section showing a number of vertical kerfs angularly disposed with relation to each other and cut in the manner shown in Figs. 14 and 15; and

Figs. 17 to 24, inclusive, are diagrammatic views illustrating several modifications of the present method of mining.

In mining various materials, and particularly coal, it is extremely desirable and important that the coal be mined with as little waste as possible and that it be mined in large regularly shaped blocks or masses so that it may be conveniently handled, not only in removing it from the mine but for shipping it and transporting it. The desirability and advantage of taking coal out of the mines in as large blocks as possible is apparent when it is realized that the transportation of coal is not only greatly facilitated by the ease and convenience with which the large blocks may be packed for shipment in the cars, but because of the fact that large unbroken masses of coal retain their efficiency much longer than coal which is broken into relatively small particles when exposed to the influences of the weather. In the drawings, and particularly in Figs. 12, 13 and 17 to 22, inclusive, there is diagrammatically illustrated the improved method of mining coal by which all of these advantages are obtained. Fig. 13 illustrates diagrammatically a longitudinal vertical section through a vein of coal, and Fig. 12 diagrammatically illustrates the forward end of the vein, that is, the end of the vein at which the mining operations take place.

In carrying out the improved method it is preferred, first, to make a plurality of vertical parallel cuts or kerfs X which preferably extend in vertical planes from the lower faces X¹ of the vein to the upper faces X² thereof. That is, vertical kerfs or cuts extend between what is gen-

erally referred to as the upper and lower faces of the vein. The upper faces X² are the faces of the vein which are exposed to the cutting mechanism, and the lower faces X¹ are the faces of the vein which are not exposed to the cutting mechanism.

After the vertical parallel cuts or kerfs X have been made, the coal is then broken into relatively large blocks or masses by means of a cutting mechanism which is actuated by the power transmitted from the motor to the cutting mechanism.

The cutting mechanism is actuated by the power transmitted from the motor to the cutting mechanism, and the cutting mechanism is actuated by the power transmitted from the motor to the cutting mechanism.

The cutting mechanism is actuated by the power transmitted from the motor to the cutting mechanism, and the cutting mechanism is actuated by the power transmitted from the motor to the cutting mechanism.

The cutting mechanism is actuated by the power transmitted from the motor to the cutting mechanism, and the cutting mechanism is actuated by the power transmitted from the motor to the cutting mechanism.

The cutting mechanism is actuated by the power transmitted from the motor to the cutting mechanism, and the cutting mechanism is actuated by the power transmitted from the motor to the cutting mechanism.

erally known as the points of cleavage between the stratum or vein of coal and the earth or ground, between which the vein of coal is confined. These cuts or kerfs X are preferably as thin as possible so as to avoid any more coal cuttings than is necessary, and they extend longitudinally into the vein to a distance which is found suitable or advisable under the particular circumstances and requirements. The kerfs X 10 are likewise spaced apart at such distances as found to be best adapted to the particular conditions and requirements. There are also made a plurality of long horizontal kerfs X^3 , X^{31} preferably extending from one side of the vein of coal 15 to the other side thereof so as to divide the vein into a plurality of large blocks X^4 , X^5 , X^6 . These horizontal kerfs, as shown in Fig. 13, lie in planes which are disposed at an angle to the longitudinal axis of the vein. They preferably begin at points 20 X^7 , X^8 below or above the longitudinal center of the vein and extend angularly upwardly and downwardly from said respective points preferably to the roof and floor of the mine entry, although it has been found that these horizontal 25 kerfs need not extend all of the way to the roof or floor of the mine entry under certain circumstances. For instance, in Figs. 17 and 18, it will be noted that the horizontal kerfs X^3 , which incline upwardly toward the roof of the mine entry, 30 may terminate short of the roof and leave an uncut portion X^9 which must be broken when blocks of coal are dislodged, while the kerfs X^{31} , which incline downwardly toward the floor of the entry, may, if desired, extend all the way to the 35 floor or line of cleavage. These uncut portions X^9 , however, are preferably not sufficiently thick to prevent blocks of coal being readily dislodged or broken away after the kerfs are cut.

As shown in Figs. 13 and 18, the series of horizontal kerfs X^3 are preferably parallel with respect to each other, and likewise the series of horizontal kerfs X^{31} lie in planes parallel with respect to each other. In consequence there are left uncut portions X^{10} and X^{11} between said kerfs 45 along the lines of cleavage both at the roof and floor of the mine, and after the kerfs have been made these blocks may be dislodged or broken away from these lines of cleavage in any suitable manner under the particular circumstances or 50 they may be severed by horizontal kerfs.

In practice, it is preferable to make a series of vertical kerfs first and after these vertical kerfs are cut then cut the horizontal kerfs, because it can readily be seen that if the horizontal kerfs 55 X^3 were made first there would be a large mass or long slab of coal suspended from the roof of the mine which, under the conditions in some mines, would be likely to fall owing to the fact that the adhesion of the slab of coal to the roof 60 of the mine along the cleavage line X^{10} would not be sufficient to support the slab of coal. Often this is true even when the vertical kerfs are made first and the horizontal kerfs afterward but in such cases, as the horizontal kerf advances across 65 the vein intersecting the vertical kerfs and forming the complete blocks X^4 , it is preferred to jack up or support the blocks X^4 until the horizontal kerfs are completed clear across the vein.

Any suitable means for supporting these cut 70 blocks may be employed, such, for instance, as jacks X^{12} of the character illustrated in Figs. 12 and 13. These jacks are provided with broad bases X^{13} and with standards which are inclined substantially parallel to the planes of the horizontal kerfs, and the heads X^{14} of these jacks

are formed as supporting members, as shown in Fig. 13, for engagement with the lower corners of the blocks. These jacks are preferably provided for each block X^4 of coal as the block is cut and when the complete series of blocks have been formed the jacks may then be removed and the blocks allowed to drop or be dislodged for removal from the mine. 80

The advantage of supporting the blocks X^4 in position until all of them have been cut is that the machine, if the machine is used, which cuts the kerfs may be moved out of the way in order to permit the convenient removal of the blocks. The cutting of the horizontal kerfs X^3 and X^{31} is preferably done alternately with respect to each other. That is to say, after the vertical kerfs are cut a horizontal upwardly inclined cut X^3 is cut. Then the blocks X^4 may be dislodged and removed from the mine entry, thus leaving the face of the coal clear so that the next horizontal cut X^{31} which begins at point X^8 and inclines downwardly, may be cut, thus leaving the lower blocks X^5 in condition to be broken along the lower cleavage X^{11} and removed from the mine. It has not been found necessary to support the lower blocks X^5 by means of jacks or otherwise, because they are resting upon the floor of the mine, so to speak, and there is not the tendency for them to fall away or break along their lines of cleavage without the aid of a slight additional dislodging force being applied to them. Of course, the vertical kerfs X should be made deep enough in advance of the cutting of the horizontal kerfs so that the blocks will be cut on all sides except along the lines of cleavage and 100 at the portions X^9 (Fig. 18) when the kerfs X^3 are not extended all the way to the roof of the mine. It is to be understood, however, that the horizontal kerfs may be made before the vertical kerfs because in some mines there is found no 105 tendency of the slabs of coal to fall of their own weight, but this, of course, is to be determined by the conditions in the particular mine in which the coal is being cut.

Figs. 20 and 22 diagrammatically illustrate a 110 modification in the angular relations of the cuts. In these figures it will be noticed that the horizontal kerfs X^3 and X^{31} begin at points X^{15} above and below the longitudinal center of the vein; that is to say, the cuts X^3 and X^{31} are disposed 115 entirely above and below the longitudinal center of the mine, respectively. It will also be noted that these kerfs X^3 and X^{31} do not incline at as great an angle with respect to the longitudinal axis of the mine as they do in Fig. 13. In consequence, it follows that center blocks X^{16} are cut on all sides except for a small portion X^{17} at the ends of the blocks which must be broken to dislodge the blocks, but, of course, this portion X^{17} 120 should not be of sufficient thickness to prevent the blocks being readily broken by relatively slight force. In Fig. 20 the horizontal cuts X^3 and X^{31} do not reach entirely to the lines of the cleavage as is the case with the kerfs X^{31} of Fig. 18, but as shown in Fig. 22, these cuts may extend 125 entirely to the line of cleavage, if desired. In Fig. 22 it will be noticed that the center blocks are completely cut on all sides; that is to say, the kerfs X^3 and X^{31} are extended into the center blocks X^{16} until they intersect or meet at the point X^{18} , thereby making complete cuts on all 130 sides of the blocks.

Figs. 23 and 24 are diagrammatic views illustrating the present improved method wherein is cut a plurality of horizontal parallel kerfs X^{19} . 135

150

These kerfs lie in planes spaced apart but substantially parallel with the longitudinal center of the vein. Any number of these kerfs may be cut, depending, of course, upon the size of the 5 vein and the particular operating conditions, although in the drawings there is illustrated only three horizontal kerfs, one being located at the upper line of cleavage of the vein, another being located at the lower line of cleavage and a third 10 substantially in the center of the vein. There is also cut a plurality of preferably parallel upright kerfs X^{20} extending longitudinally into the vein and intersecting the horizontal kerfs X^{19} so as to cut the blocks of coal on all sides except at their 15 inner end portions X^{21} , which portions are left uncut. Under ordinary circumstances these uncut portions X^{21} will be broken by the weight of the blocks themselves and the blocks will drop one upon the other in stacks, so to speak. In the 20 event that the conditions in the particular mine are such that the uncut portions will not be broken by the weight of the blocks themselves, then they may be broken in a suitable manner by applying a suitable force thereto to break along the uncut 25 portions. It will be noted that the upright kerfs X^{20} are inclined at a small angle with respect to a vertical line, and the object in doing this is to facilitate the cutting of the kerfs by mining machines. By inclining the upright kerfs to a small 30 degree it will be noted that the breaking of the uncut portions X^{21} by the weight of the blocks and the dropping of the blocks will not interfere in any way with the cutting mechanism of the mining machine. In other words, the blocks will 35 drop directly away from the cutting mechanism and allow the cutting mechanism to be withdrawn after the kerfs are made. In the method shown in Figs. 23 and 24, the horizontal kerfs X^{19} are preferably cut first and then the upright kerfs 40 are cut one by one in sequence beginning with the right-hand kerf X^{20} and proceeding with the cutting of these kerfs entirely across the end of the vein.

In Figs. 1 to 11, inclusive, there is shown a 45 mining machine by means of which the cutting of the various kerfs at the various angles as above described, may be readily and conveniently accomplished.

In the structure which is shown in the drawings, 50 it is preferable to use a flat elongated cutting bar or cutting mechanism A, shown best in Figs. 1, 2 and 3 and in detail in Figs. 3 and 3^a, because it is thereby enabled to cut comparatively thin kerfs or cuts without producing any considerable 55 amount of cuttings. The details of the present preferred cutting mechanism structure will be described hereinafter. It is sufficient at this time to say that the cutting mechanism is in the form of a long flat comparatively thin structure having 60 a cutting chain B traveling preferably in one direction around its periphery so as to form a peripheral edge, so to speak. This cutter bar is preferably comparatively narrow in width and is preferably made of such length as to meet the desired 65 requirements as to depth of cut, etc. This cutter bar or kerf cutting mechanism is mounted to cut kerfs at both sides of the mine track as well as in advance thereof, at the floor, at the roof and at various intermediate elevations, by rectilinear 70 feeding movements and arcuate feeding movements along horizontal lines, and in addition the same kerf cutter can produce upright kerfs or shearing cuts and slanting kerfs intermediate horizontal and vertical planes. The machine is track 75 mounted and is operable in rooms of widths vary-

ing from that somewhat greater than the width of the mine track to twice the longer radius of swinging movement of the cutter bar. There will now proceed, therefore, a description of a mechanism by which these positions and cutting movements are brought about. 80

The entire machine is preferably mounted upon a wheeled truck C, the wheels 1 of which are preferably mounted upon suitable axles 2 and adapted to run on rails 3 laid along the floor of the mine or entry or other line of movement along which the machine is to operate. The rails 3 are preferably supported by metal ties 4 transversely arranged at intervals and having upturned ends 5. The rails are laid on the ties adjacent the upturned ends 5 of the ties and are prevented from spreading or shifting by means of blocks 6 disposed between the rails and the upturned ends of the ties and by means of spikes or other suitable fastening devices 7 arranged to engage the base of the rails, as shown more clearly in Figs. 1 and 4. The truck is shown as having a large flat platform or table 8 upon which the mining machine is mounted. 85

This truck platform has a large depending socket or dish-shaped depression 9. Above the platform, and preferably disposed parallel with respect thereto is a large circular table or platform 10 which serves as a turntable and which has a central vertically disposed shaft or bearing member 11 (Fig. 1) rotatably sunk into the socket or bearing number 9 of the truck platform, whereby the turntable 10 may be rotated about the vertical axis of its shaft or pivot member 11. The entire mining machine is preferably mounted 100 upon or supported by this turntable so that it may be bodily swung or rotated about a vertical axis to position the cutting mechanism with respect to the material to be cut. 105

It is preferred that the turntable with the mining machine mounted thereon shall be capable of bodily vertical adjustment, and for this purpose any suitable mechanism may be provided. In the drawings (Figs. 1 and 4) there is illustrated a screw member 12 threaded through the bottom of 110 the bearing member 9 and operating against the lower end of the shaft or pivot member 11 whereby the turntable may be raised or lowered with respect to the truck, as desired. The turntable is provided with power-actuated means comprising 115 120 the worm gear 15 and the large gear 16, and for the sake of simplicity in illustration the worm gear 15 is shown operated by a hand wheel 17, although it should be understood that it may be operated by means of any desired mechanism. As shown 125 in Fig. 4 the worm gear 15 is connected to a shaft 13 which is suitably journaled in an upstanding arm or bearing 14 on the truck and having at one end a worm wheel 15 which meshes with gear teeth 16 on the periphery of the turntable 10, 130 135 and having at its other end a suitable hand wheel 17 (as shown in Figs. 1 and 4) by which the shaft may be conveniently rotated by an operator or attendant standing at the side of the machine.

A pair of open, preferably rectangular, frames D 140 are rigidly mounted upon the turntable 10 in any suitable manner. These frames are parallel and are spaced apart. The upper and lower bars or members D¹, D² respectively, of each of these frames, are parallel and are adapted to form 145 guides or tracks for a pair of sliding standards 19 and 20, respectively. These sliding standards are suitably formed at their upper and lower ends to embrace the track bars D¹ and D² of the frames to prevent displacement of the standards in any 150

direction except along the track members of the frame. These standards are rigidly connected together at their bases by a platform member 21 so that they, in conjunction with the platform 21, 5 constitute a sub-frame which may be rigidly shifted horizontally in the main frames D, as above described, and by means of this arrangement the entire cutting mechanism may be bodily shifted to any position within the limits of this shifting or 10 sliding adjustment.

The shifting of this sub-frame and the mechanism supported thereby may be accomplished in any suitable manner consistent with the conditions and requirements. In the drawings there is 15 shown power-operating mechanism for this purpose. On the sub-frame platform 21 is mounted an electric motor 22, the electric connections for which may be brought to the motor in the usual manner and which need not be described. The 20 motor shaft is supported in an outer bearing 23 and carries at its end a pinion 24 which drives a larger spur gear 25, this spur gear being mounted to drive a counter-shaft 26 supported in bearing standards 27. This counter-shaft carries a rotatable sleeve 28 which is provided with a worm gear 29, and which may be connected with or disconnected from the counter-shaft 26 by any suitable clutch mechanism such, for instance, as is shown in the drawings.

It will be seen that the inner end 30 of the sleeve is provided with notches or teeth so as to 30 form one member of a clutch. The other member 31 of the clutch is mounted upon the shaft 26 to rotate therewith and to slide longitudinally 35 thereof, and this member 31 may be thrown into or out of engagement with the clutch member 30 by the hand-operated lever 32 pivoted at one end to the platform 21. Hence, by operating this hand lever the worm wheel may be connected 40 with the shaft to be driven thereby or disconnected from said shaft at will.

The worm gear 29 meshes with and drives a worm gear 33 which is mounted upon a vertical shaft journaled in a bearing mounted upon the 45 platform 21. The shaft carries a horizontally disposed winding drum or capstan 34, and as this capstan may be used as a means for shifting the sub-frame in the main frame, as shown in Figs. 2 and 4, a jack 35 may be placed at a proper position in the mine entry and a rope or cable 36 hooked thereon and run to the capstan or drum 34 so that by permitting the cable to wind upon the drum the sub-frame may be shifted in the main frame. Any suitable anchor may be used for the 50 end of the rope, but it is preferred to use a jack 35, such as shown in Fig. 4, because it may be conveniently handled and moved about from place to place.

The upper portions of the standards 19 of the 55 sub-frame carry a large heavy bar or member 40 preferably of rectangular cross-section and arranged to slide or shift longitudinally in suitable bearing members 41 of the sub-frame standards. This bar is preferably of considerable length so that it will have quite a long range of movement. It will be noted that the line of movement of this bar 40 is disposed at right angles or transversely to the line of bodily movement of the shifting sub-frame so that by reason of this construction, in conjunction with the sub-frame, the cutting mechanism may be bodily shifted or adjusted in two directions at right angles to each other thereby allowing a wide range of bodily adjustment for the cutting mechanism.

The shifting of this bar 40 is accomplished through the medium of gear mechanism interposed between the bar 40 and the driving motor 22. As shown more clearly in Figs. 1, 2 and 4, it will be seen that the entire underside of the bar or member 40 is provided with a series of gear teeth 42 thereby constituting a rack bar. A driving pinion 43 meshes with these rack teeth for imparting longitudinal movement to the shifting bar 40, and the pinion 43 is mounted upon a shaft 44 which is journaled in bearings 45 depending from one of the rack bar bearings 41.

One end of the shaft 44 carries a large worm wheel 46 which meshes with and is driven by a worm gear 47 similar to the worm gear 29, and which is carried upon a rotatable sleeve 48 on shaft 26 similar to the sleeve 28. This sleeve 48, like sleeve 28, forms one member of a clutch, the other member 49 of which is rotatable with shaft 26 but slideable thereon, and this clutch member 49 is adapted to be shifted into and out of engagement with the sleeve 48 by the hand lever 50. Thus the movement of the shifting rack bar 40 may be controlled at will, and by reason of the worm gearing just described the 100 rack bar will remain locked in any position to which it is moved without the necessity of additional locking means.

At one end of this rack bar 40 is provided an arm or member 51 which is disposed downwardly 105 for a portion of its length and then turned horizontally into substantial parallel relation with the longitudinal axis of the rack bar 40. The longitudinally disposed portion of this depending arm forms a pivot member or stud 52 upon which 110 a forked support E is rotatably mounted.

By reference to Figs. 1 and 2 it will be noted that the supporting member E has a centrally disposed bearing portion or stem E¹ which is rotatable upon the pivot member 52, and it may 115 be held in place upon this pivot member by means of an annular shoulder 53 on the arm 51 and a removable cap 54 which is fastened to the end of the stud member 52 by means of a screw or bolt 55. Thus by this construction the forked support 120 E is capable of rotary movement upon an axis which is substantially parallel with the longitudinal axis of movement of the rack bar 40, such axis being substantially transverse to the vertical axis of rotation of the turntable upon 125 which the machine is mounted.

For the purpose of rotating this forked support E about its axis in a convenient manner, there is provided a worm wheel 56 on the bearing portion E¹ of the support E and this worm wheel is driven by a worm 57 which is mounted upon a shaft 58 supported in a suitable bearing 59 outstanding from the end of the rack bar 40. The shaft 58 has a hand wheel 60 by which it may 135 be conveniently actuated by the operator to adjust the position of the support E. It will be noted that by reason of the worm gear arrangement the support E will be automatically locked in any position to which it is rotated without the need of additional locking mechanism.

An electric motor F is rotatably supported in the forked support E. In the drawings, there is shown a pair of brackets 61 bolted to the motor casing F on diametrically opposite sides thereof, and these brackets carry outstanding trunnions 145 62 arranged in alignment and suitably journaled in the outer or free ends of the arm members E² of the support E so that the motor F may be rotated about an axis 62 which, as shown in Fig. 1, is disposed substantially at right angles to 150

the horizontal axis of rotation 52 of the forked support E.

It will be noted that the arms E² of the support E are curved as shown in elevation in Fig. 1 so that the axis of rotation 62 of the motor in the support E is offset to a considerable extent with respect to the horizontal axis of rotation of the support E at 52. This construction is of advantage in that it will enable the cutting mechanism to operate through a greater range than otherwise.

One of the brackets 61 carries a rigid segmental worm gear 63 which extends over any arc desired. The worm gear 63 meshes with and is adapted to be driven by the worm 64. This worm is mounted upon a small shaft 65 which is carried in a journal bearing 66 extending from one of the arms E² of the support E, and the shaft 65 also carries a hand wheel 67 by which it may be manipulated to rotate the motor about its axis 62. The worm gearing 63, 64 being self-locking as in the other cases heretofore mentioned, makes it possible to eliminate special locking means for holding the motor in any position to which is adjusted.

The cutting mechanism or cutter bar A is carried by a frame or casing member 70 which is rotated on an axis 81 transverse or at right angles to the axis 62 of rotation of the motor in the forked support E, whereby the cutting mechanism may be arcuately fed or swung in the plane of itself through a considerable range and thus permit a much wider cut or kerf to be made than if the cutting mechanism were fixed with respect to the motor which drives it. As shown in the drawings, the frame or casing 70 has an internal peripheral groove 71 formed at its edge and this groove fits an annular flange 72 on the motor casing so that a bearing is provided upon which the casing 70 may rotate. A removable flange or cap ring 73 is bolted to the casing 70 to permit the parts to be readily disassembled. This casing, together with the motor casing, as will be noticed, forms a complete enclosure for the various gears and operating parts contained therein, leaving none of these operating parts exposed to the grit and dust which necessarily results from the cutting operation.

Referring more particularly to Figs. 5 and 6, it is to be understood that F¹ represents the field magnets of any standard or suitable motor, and F² the armature thereof, the armature being mounted upon the motor shaft F³ and journaled in ball-bearings F⁴ in the head or end of the motor casing F. The motor shaft F³ projects beyond the bearing and carries a spur pinion 75 which drives a larger spur gear 76 carried by a shaft 77, the shaft having its bearings 78 in a bracket preferably formed integrally with the casing 70. This shaft also carries a spur pinion 79 which drives the large spur gear 80, which latter gear is mounted upon and adapted to drive a shaft 81 journaled in the frame or casing 70. The purpose of operating this train of gears thus described is to reduce the relative speed of the shaft 81.

The shaft 81, as will be noticed, is lined up with the motor shaft F³ and carries at its outer end a sprocket 82 around which the cutter chain travels and by which said cutter chain is driven, as will be hereinafter described. The inner end of the shaft 81 carries a beveled gear 83 which is adapted to drive two small radially disposed shafts 84 and 85 through the medium of two small beveled pinions 86 which are carried by the

shafts 84 and 85 and which mesh with the beveled gear 83. The other ends of the shafts 84 and 85 carry beveled pinions 87 and 88, respectively, which are mounted upon sleeves so that the gears may rotate with respect to their shafts. These sleeves are notched at their ends 89, 90 to form clutch members and are arranged to be connected with their shafts for rotation therewith by means of sliding clutch members 91 and 92, respectively.

The beveled gears 87 and 88 mesh with corresponding beveled gears 93 and 94 carried at opposite ends of a shaft upon which the worm gear 95 is mounted, the shaft which carries this worm gear being suitably journaled in bearings in the casing 70. This worm gear 95 meshes with an annular series of gear teeth 96 formed upon the motor casing F. Hence by driving the worm gear 95 in either direction the casing 70 may be rotated relatively to the motor on an axis 81 which in this case is coincident with the axis of rotation of the motor shaft, and since the cutter bar A is mounted upon this casing 70 the cutter bar will be given a bodily rotation about said axis 81. Thus by reason of this construction the cutter bar or cutting mechanism may be rotated in the plane of itself while the cutter chain is traveling around the cutter frame 105 (Fig. 3). By simply shifting one or the other of the clutch members 84 and 85 it is obvious, of course, that the gear 87 or gear 88 may be thrown into or out of operation to drive the worm gear 95 in whichever direction is desired.

In Fig. 5 there is shown a device by which either of these clutch members may be shifted from either of two different points. There is provided a rigid lever which is centrally pivoted at 97 to the casing 70 and which has two bent arms which are connected to the clutch members 91 and 92. These bent arms project through openings 99 in the casing or frame 70 in position to be actuated by an operator for controlling the clutches. The advantage of providing two points of control for either of these clutches lies in the fact that in case one of the arms 98 is not in convenient position for the operator to manipulate, the other arm will be.

One of the edges of each of the openings 99 in the casing 70 has three depressions 100 (see Fig. 7) corresponding to the different positions to which the respective arm is shifted, and the arms are each provided with a slight enlargement 101 adapted to enter these notches or depressions in the edges of the casing and hold the arms in the positions to which they are shifted, the arms being made to spring slightly so that they will be held in the notches by the tension thereon.

Referring more particularly to Figs. 1, 2, 3, 3^a and 6, the details of the cutting mechanism or cutter bar A will now be described. This cutter bar has a flat elongated frame 105 around the edge or periphery of which the cutter chain travels. The cutter frame 105, as will be noticed, lies in substantially the plane of the sprocket 82 so that the sprocket and frame will be properly lined up to accommodate the chain. The end of the cutter frame 105 nearest the sprocket 82 has an offset tailpiece or extension 106 which is disposed substantially parallel with the frame itself but is adapted to slide in the guideway 107 formed in the frame or casing 70, this tailpiece or extension being provided with a slot 108 for the accommodation of the bearing portion or journal 109 for the shaft 81; the purpose of this construction being to allow the

frame 105 to be adjusted longitudinally in either direction relatively to the sprocket 82, for the purpose of tightening or loosening the cutter chain or for the purpose of shortening or lengthening this chain, as will be hereinafter described.

The journal or bearing portion 109 of the frame 70 carries a headed bolt or screw 110, the head 111 of which is positioned in a slot in the hub portion 109 so as to prevent movement of the bolt in either direction. This bolt extends through an opening in the end 112 of the tail-piece 106 and is provided with two nuts 113, the purpose of the bolt and nut being to hold the cutter frame 105 in any position to which it is longitudinally shifted.

As shown more particularly in Figs. 3 and 3^a it will be seen that the cutter chain is composed of a plurality of middle or center links 115 and a plurality of intermediate side links 116. The middle or center links 115 are preferably provided with removable cutting knives, bits or cutters 117, and are adapted to slide along the peripheral edge 118 of the cutter frame. The side links 116 project beyond the middle of center links so as to form, in a sense, a continuous channel on the inside of the chain, and the cutter frame has shoulders 119 formed near its edge to accommodate the side links 116. In this manner the chain is, in a sense, interlocked with the cutter frame 105 and may travel around the edge of said cutter frame without danger of being displaced laterally. It will be noted that the faces of the cutter frame 105 are substantially flush with the outer faces of the side links 116 so as to provide a structure of uniform thickness capable of entering the kerfs. Of course the cutting knives or cutter bits 117 on the chain are slightly wider than the thickness of the frame and chain. It is found desirable to allow the cutter chain to travel around the outer end of the cutter frame, this being a sufficient support for the chain without adding any undue friction, but, if desired, a sprocket wheel 120 may be provided at the outer end of the cutter frame, as shown in Figs. 3 and 3^a.

In Figs. 8, 9, 10 and 11, there is illustrated a modification of the present improved machine wherein has been eliminated the motor F which is positioned in the forked support E in Fig. 2, and gearing has been substituted therefor, which gearing is driven by the motor 22 mounted upon the sub-frame. This arrangement enables one motor of a larger capacity to be used for the purpose of driving and actuating a cutting mechanism and also for bodily shifting the parts.

The shaft of the motor 22 carries a pinion 125 which drives a large gear 126 mounted upon a suitable shaft which is supported in the bearing standards 127 on the sub-frame platform 21. This large gear 126 in turn meshes with and drives one of two inter-meshing gears 128 of equal size, these gears 128 being mounted on separate parallel shafts 129 and 130 which are supported in suitable bearings 131 on the platform 21. These shafts also carry worms 132 and 133 which drive two large worm gears 134 and 135, respectively, mounted to rotate upon the shaft 44 which carries the pinion 43 for shifting the rack bar 40, the shaft 44 being supported in suitable bearings which are altered in accordance with the changes of construction in this modification.

The gears 128 rotate in opposite directions and in consequence drive the large worm wheels 134 and 135 in opposite directions these gears being

free to rotate upon the shaft 44. Between the two gears 134 and 135 is provided a shiftable clutch member 136 which may be shifted on the shaft in either direction in the usual manner to connect one or the other of the gears 134 and 135 with the shaft 44 to drive said shaft in either direction and thereby reciprocate or shift the rack bar 40 in either direction without reversing the motor.

The shaft 140 upon which the large gear 126 is mounted, is preferably of substantially the length of the shifting or reciprocating rack bar 40 and parallel therewith. This shaft is arranged so that it will slide longitudinally with respect to its bearings and the gear 126 in accordance with the movement of the rack bar. It is preferably squared or otherwise formed, however, so that it will be rotated by the gear 126 at any position into which it is shifted. This shaft 140, which is round at its right-hand end, extends through a bearing formed in the horizontal or pivot portion 52 of the depending arm 51 and projects into the space between the two arms or parts E² of the rotary forked support E, and carries a beveled pinion 141 on this projecting end. It also carries a collar 142 which takes the place of the cap member 54 of Fig. 1 to prevent the support E from being displaced with respect to the pivot portion 52 but to allow it to be rotated about its axis in the same manner and preferably by similar hand-operated means to that shown in Figs. 1 and 2. The beveled pinion 141 meshes with and drives a larger beveled gear 143 which is rotatably mounted upon a fixed shaft 144, the longitudinal axis 110 of which lies at right angles to the axis of rotation of the forked support E in the same manner that the axis of rotation of the motor F of Fig. 1 bears with respect to said axis 52. This shaft 144 has its bearings 145 in the ends of 115 the arms E².

Between the beveled gear 143 and one of the journals 145 is an arm 146 having its hub 147 pivotally mounted upon the shaft 144 so that the arm may be swung or rotated about the axis of 120 the shaft 144. This arm 146 and its manner of mounting may be said to correspond to the motor F (Fig. 1) insofar as the movements thereof are concerned. The outer end of this pivoted arm 146 has a bearing 148 and a large head or flange 125 149 which may be said to correspond to the flange 72 of the construction shown in Figs. 5 and 6.

The casing 70 is mounted to rotate upon the flange or head 149 in the same manner as in the construction shown in Figs. 5 and 6 and the details of this casing and its cutter mechanism carried thereby are similar to the construction previously described and the description thereof need not be repeated. The shaft 81' which carries the cutter chain sprocket 82' is similar to 125 the corresponding shaft of Figs. 5 and 6 except that it is not driven from a series of reducing gears within the casing 70 but instead it passes directly through the head 149 and is journaled in the bearing 148. On its inner end it carries a beveled pinion 150 which meshes with and is driven by the large beveled gear 143 and in this way receives its motion direct from the main motor 22 on the sub-frame platform 21.

The arrangement of the beveled gears 141, 143 and 150 thus permits the cutter chain shaft 81' to be rotated, regardless of the angle or position to which the arm 146 is rotated about its axis.

A hand wheel 67 and the self-locking worm and segmental worm gear 64 and 63, respectively, of

the construction shown in the preceding figures for rotating or positioning the arm 146, is employed except that the segmental gear 63 in this case is mounted upon the hub 147 of the arm 146.

- 5 The operation of the mechanism for rotating the casing 70' and the cutter mechanism about its axis is identical in principle and the arrangement of the parts, to the construction shown in Figs. 5 and 6, except that worm and spiral gear-
10 ing is employed on the shafts 81', 84' and 85' instead of the beveled gears 83, 86, 87, 88, 93 and 94. The annular series of gear teeth 96, with which the worm gear 95 meshes, is mounted on the face of the head of the flange member 149; 15 this gearing is self-locking.

It has been previously mentioned that the above described apparatus or machine is capable of and adapted to cut the various kerfs at their various angles in order to carry out the improved 20 method of mining above described. In Fig. 14 is diagrammatically illustrated the manner in which the machine may be manipulated to produce the horizontal kerfs X^{19} of Fig. 24 or the vertical kerfs X of Fig. 12 heretofore described. When 25 it is desired to cut a vertical kerf in the vein of coal the cutter bar A, by reason of its numerous adjustments, may be positioned so that it will lie in a vertical plane. Since the height of the vein of coal is generally considerably greater than 30 the width of the cutter bar, it is preferred to start the kerf by positioning the cutter bar so that it lies in a vertical plane but inclined upwardly at such an angle that its outer end coincides with the roof of the entry or the upper line 35 of cleavage.

The cutter bar is diagrammatically illustrated in Fig. 14 by the dotted lines Y. The outer end of the cutter bar in this position is presented to the end of the face of the wall or end of the vein 40 into which it is to operate and the cutter mechanism advances into the vein in the direction of the arrow Y^1 , while in its angularly adjusted position. The advancement of the cutting mechanism is preferably accomplished by shifting the 45 rack bar 40, as previously described. The advancement in this direction is continued until the cutter bar has entered the vein to the required depth or distance, and since its chain is traveling during this advancement it cuts along the 50 upper line of cleavage. When it has reached the limit of its advancement the cutter bar may be swung or rotated downwardly in the direction of the arrow Y^2 but still in the plane of itself until its outer end reaches the lower line of cleavage, 55 whereupon with a suitable cutting speed, it may be withdrawn from the vein while in this last-mentioned adjusted position, the direction of withdrawal being that indicated by the arrow Y^3 . In other words, to cut a vertical kerf of 60 greater height than the width of the cutter mechanism, the cutter mechanism may be moved in three or more directions all in the same plane. It will be observed that a mining machine construction is provided wherein the cutting mechanism is universally movable or adjustable; that 65 is to say, it may be placed in any position at any angle at which it is desired to cut a kerf.

It should also be understood that when the trunnion arms E^2 are in the position shown in 70 full lines in Fig. 1, the casing 70 may be swung on the trunnions 62 by operating the wheel 67. In this way, the cutting mechanism or cutter bar A may be swung around so as to occupy a position in a horizontal plane at or near the floor 75 of the mine. After the cutter bar has been

brought to this position in the horizontal plane, it may be swung on its pivotal connection with the casing 70 by operating the electric motor within the casing F. Power may be transmitted from this motor to swing the cutter bar in one 80 direction or the other on its pivotal connection with the casing 70 by operating the lever 98 at one side or the other of the casing 70, as shown in Fig. 5.

It is also evident that the feeding mechanism 85 for moving the trunnion arms E^2 operates independently of the mechanism for controlling the lateral swinging movements of the cutter bar A. By throwing in the clutch 49, the electric motor 22 may be connected to the feed mechanism at will, and by reversing the electric motor the feed mechanism may be reciprocated whenever desired. Obviously, therefore, the cutter bar A, while occupying a horizontal position, may be swung at an angle and then moved bodily forward by the feed mechanism while the cutter chain is in operation, thereby producing a cut in the mine wall. Furthermore, after this cut has been produced to the required depth, the cutter bar may be swung laterally while the cutter chain is operating, and at the same time the rear portion of the cutter bar may be retracted until the cutter bar occupies a position substantially at right angles to the body of the truck 100 on which the mining machine is mounted. Upon 105 continued swinging movement of the cutter bar, the feed mechanism may be reversed so that the rear portion of the cutter bar will be fed forward during continued operation. By means of this operation, the forward portion of the cutter bar 110 travels over a path which is approximately a straight line.

After the cutter bar has been swung in the opposite direction as far as desired, the swinging movement may be discontinued, and, while the 115 cutter bar still occupies the position at an angle to its pivotal connection to the casing 70, the motor 22 may be reversed so as to cause the feeding mechanism to be drawn back while the cutter bar is still operating. It will thus be seen 120 that a square or rectangular cut can be produced in the mine wall, each side of which is approximately a straight line, as well as the base of the cut. The forward end of the cutter bar, during 125 the swinging movement, tends to move over an arc of a circle determined by the angle of the swing, but the reciprocation of the pivot of the cutter bar causes a resultant movement of the outer end of the cutter bar along the chord of such arc of a circle.

The cut at or near the floor of the mine has been referred to merely by way of illustration, and it should be understood that a similar cut can be made at or near the roof of the mine and also at each side wall of the mine, or even at 135 any angle to such cuts, with the exception that whenever such cuts are produced each must be in a plane parallel to the line of the path of travel of the feed bar 40, so as to prevent binding of the cutter bar in the cut.

It should be noted that the mining apparatus above described and shown in the drawings is track mounted and when the rails are extended up to a position near the face of the mine wall the mining apparatus may be swung around by 145 the turntable mechanism to a position where the cutter B may cut a horizontal kerf extending across the front of the mining apparatus from one side of the track to the other. The truck frame 8 constitutes a rigid base frame having 150

supporting wheels which rest upon and are braced by the track, as shown in Fig. 1.

The base frame carries a laterally movable cutter arm which extends from the base frame 5 in elevated horizontal planes above the other parts of the apparatus. When the frame E is swung to the dotted line position shown in Fig. 1, the kerf-cutter may easily be swung to a horizontal position in a plane elevated with respect 10 to the other parts of the apparatus. There may be a plurality of such elevated horizontal planes because the screw-threaded bolt 12 may be used to lift and lower the frame D on the truck frame 8. When the kerf-cutter is in such horizontal 15 planes its endless cutter chain is movable along the cutter arm in a path horizontal throughout. Furthermore, when the kerf-cutter is in its highest position, the motor F is a chain driving motor positioned below the cutter arm and fixedly 20 connected thereto to move bodily therewith whenever the adjusting mechanism 63, 64, is operated. Also, when the kerf-cutter is in its uppermost position the power transmission between the kerf-cutter and the motor constitutes power- 25 actuated means below the arm or frame of the chain cutter for causing such arm and the chain cutter to move laterally to cut a horizontal kerf in the elevated plane extending transversely from one side to the other of the track.

30 Although the track mounted mining apparatus cuts a horizontal kerf extending across its front from one side of the track to the other, the supporting wheels 1 which rest upon the track are braced by the track by means of the tendency 35 of the feed to twist the frame. The flanges of the wheels however, resist this twisting tendency and therefore the feeding operation can be effected. Of course the kerf-cutter B may be moved to a horizontal position from its full line 40 position shown in Fig. 1 so as to occupy its lowermost plane. But whether the kerf-cutter is in a relatively low cutting plane or in a relatively high plane, the screw member 12 constitutes means for adjusting the cutter arm vertically in 45 parallelism, and such screw member 12 in combination with the gearing mechanism 63, 64, 56, 57, constitutes means for bodily adjusting the cutter arm vertically in parallelism to move the cutter chain from one set of relatively low cutting 50 planes to another set of relative high cutting planes.

55 It is also obvious that the power-actuated means shown in Figs. 5 and 6 is constructed and arranged to cause the arm and the chain to move laterally to cut a horizontal kerf at any one of several elevations and extending transversely from one side to the other of the track. When the kerf-cutter is in its uppermost horizontal plane or in its lowermost horizontal plane the 60 screw member 12 may be relied upon for vertically adjusting the motor and the cutting mechanism in horizontal parallelism and to hold it either where it will form a kerf in relatively low horizontal planes or where it will form a kerf in other horizontal planes relatively higher than those aforesaid. In other words, the screw member 65 12 constitutes means for adjusting the motor and the cutter frame vertically for the forming of horizontal kerfs in either of several different 70 horizontal planes.

75 The forward feed of the mining machine along the track to new positions may be effected by the power driven reel shown at 34 in Fig. 4, this reel being then movable horizontally with the cutter frame. The cable 36 when anchored, as

shown in Fig. 4, and connected to the reel, is adapted to cause the forward movement, bodily, of the cutting apparatus.

It should also be observed that the mining machine illustrated in the drawings may make 80 horizontal kerfs X¹⁹ (Fig. 24) intermediate the floor and roof as well as horizontal kerfs at the floor of the mine chamber and horizontal kerfs at the roof of the mine chamber while being moved along the track in a longwall mining operation, the parts being arranged as shown in Fig. 1 to produce the kerfs X¹⁹ of Fig. 24, except that the cutter bar A occupies a horizontal position.

When the intermediate kerf X¹⁹ of Fig. 24 is desired, the frame 70 is moved to an upside down position by means of the wheel 67 and the gearing connected thereto and while this is being done the cutter-frame 105 may be swung on the axis 81 so that when the said upside down position is reached the cutter will still extend outwardly from the machine and occupy a position intermediate the floor and roof where it can cut the kerf X¹⁹ of Fig. 24 intermediate the floor and roof. In this position, as well as at the floor and at the roof, longwall operations may be carried 90 on or the operation illustrated in Fig. 14 may be carried out in a horizontal plane. Such operations as those illustrated in Fig. 14 may be carried out on either side of the mine track or in 95 advance thereof.

100 It should also be understood that when the modifications shown in Figs. 8 to 11, inclusive, are substituted for the motor F and its connections in Figs. 1, 2, 5 and 6, a self-contained mining machine results because the operations illustrated 105 in Fig. 14 may be carried out without any extraneous anchorage connections.

If the framework of the machine be jacked in 110 stationary position by means of roof jacks in a well-known manner, the rope-winding mechanism may pull the rope 36 while the free end thereof is hooked to the roof jack 35 as shown in Fig. 4, whereupon the cutter may be fed rectilinearly along the frame D by sliding the frame 19 along the ways D' and D² in a longwall operation.

115 In a similar manner the flat chain kerf-cutter A may be located in a horizontal plane at the floor in advance of the mine track with the guides D', D² extending transversely of the mine track 120 and the latter secured in stationary position by means of roof jacks while the worm gearing 15, 16 locks the turntable to the truck. Now while the sub-frame 19 is at one end of the track D', D² the cutter bar may be locked at an adjusted 125 angle by means of the worm gearing 95, 96, the rack bar 40 may be moved forwardly parallel to the mine track to effect a sumping cut along rectilinear lines parallel to the mine track, then by retracting the bar 40 while feeding the cutter 130 bar anti-clockwise on the axis 81, the cutter bar may be placed in alignment with the bar 40. By means of the rope winding mechanism comprising the rope 36 the cutter may then be fed at right angles to the longitudinal length of the 135 mine track. The straight faced cut may be completed by advancing the bar 40 while feeding the cutter bar anti-clockwise, and finally effecting a rectilinear withdrawal cut.

140 Kerfs may also be made spaced back from the face of a longwall by adjusting the plane of the kerf-cutter to a vertical plane. The machine may also be operated by making vertical kerfs at right angles to the face of the mine wall in which horizontal kerfs and kerfs spaced back 145

from the mine wall have already been produced, thereby cutting out large blocks of material from the wall each in its entirety.

From the foregoing it will be seen that the 5 turntable 10 and the framework mounted thereon constitutes a body which is turnable horizontally by means of the wheel 17 and the gearing operated thereby. The tool support E is rotatable on the horizontal axis of the cylindrical bearing 52. 10 Such rotation may be effected by the wheel 60 which drives the worm gearing 56, 57. It should also be noted that the axis of rotation of the support E on the bearing 52 constitutes an axial line for the rotatable support E. By referring to 15 Figs. 8 and 9 it will be seen that certain members support the cutting tool on the rotatable support E for movement toward and from the axial line of support. The wheel 67 and the gearing 63, 64 actuated thereby constitute means on 20 the rotatable support for actuating the supporting members for moving the tool toward and from the axial line of the rotary support.

The motor 22 being mounted on the platform 21 is connected to means comprising the shaft 140 25 extending along the axis of the rotatable support E for actuating the cutting tool. That is to say, the motor 22 being connected to the shaft 140 to rotate the latter and this shaft being connected to the sprocket wheel 82', the motor 22 30 may be mounted on the platform 21 or on the supporting framework and the driving connections relied on to operate the cutting tool, including swinging feeding movement thereof. After the adjustments have been made by the wheels 35 60 and 67, the motor 22 may be started to drive the chain of the chain-cutter and then one of the levers 98 shown in Fig. 10 may be actuated to throw in either of the clutches 91, 92, to effect swinging feeding movement of the cutter on the 40 axis of the shaft 81'. Therefore, in the construction shown in Figs. 8 to 11, inclusive, the adjustments, operations and controls are the same in Figs. 1, 5 and 6, but instead of having two motors 22 and F as shown in Fig. 1, only one motor 45 is used in Figs. 8 to 11, inclusive, namely, that designated 22 on the frame 21, the driving connections between this motor 22 and the cutting tool being such as to enable the elimination of the motor F of Fig. 1.

50 In the structure shown in Fig. 1, the motor F is carried by the rotatable support E, but in both the form shown in Fig. 1 and in the form shown in Figs. 8 to 11, inclusive, the control of swinging feeding movement by means of the clutches 91 and 92 is such that when the cutter is parallel to the axial line of the rotatable support E, the cutter may be swung to cut a kerf in a plane parallel to such axial line.

When the turntable 10 is swung by means of the wheel 17 to a position where the axial line of the rotatable support E is parallel to the mine track with the cutter flat on the floor in advance of the mine track, the cutter may be adjusted at an angle so that when the whole machine is moved along the mine track by means of the rope-winding mechanism shown in Fig. 2 65 while the free end of the rope 36 is anchored to the coal face, a rectangular sumping cut may be made at the base of the mine vein. If the framework of the machine is held stationary by means of roof jacks, the rack bar 42 may be operated to effect a similar rectilinear feeding movement. After such sumping cut has been made, the cutter may be swung on the axis of the shaft 70 81 or 81' so as to secure an arcuate cut, as illus-

trated in Fig. 14 by the arrow Y², considering this view as a plan view. After such swinging feeding movement is effected, a withdrawal cut may be made, as indicated by the arrow Y³, either by the rope-winding mechanism shown in Fig. 4 80 or by retracting the bar 40, as above explained. Similar operations may be carried on at the roof and also intermediate the floor and roof.

Whether operating at the floor or at the roof or intermediate the floor and roof to secure one of the horizontal kerfs shown in Fig. 24, accuracy of adjustment in elevation of the cutter-bar may be obtained by means of the elevating screw 12 shown in Fig. 1 which may be designed to have sufficient power to lift the framework of the machine while the latter is guided and kept from tilting by means of the guiding structure shown in Fig. 1^a. The extent of vertical adjustment by means of the lifting screw 12 may be increased by increasing the depth of the receiving cup for the parts shown at 10 and 11 in Fig. 1^a and the gear 16 may be widened correspondingly to prevent the same from running out of mesh with the worm 15 shown in Figs. 1 and 4.

It should be particularly noted that the worm 100 gearing illustrated in the accompanying drawings is all of the automatic locking type. Such locking worm gearing is particularly useful in connection with the holding of the cutter-bar at an adjusted angle while being fed rectilinearly parallel to the mine track for either the making of a sumping cut or for the making of a withdrawal cut, and during such sumping and withdrawal cuts the worm gearing 15, 16 automatically locks the turntable against swinging movement relatively to the truck.

When the shaft 81 or 81' occupies a vertical position, the gearing 15, 16 constitutes means for shifting the vertical axis 81 or 81' laterally relatively to the main frame while maintaining 115 this axis upright. The worm gearing 15, 16 being of the locking type holds the cutting element rigid relative to the main frame in its various positions to which it is shifted laterally. The worm gearing 95, 96 is also of the locking type so 120 that the cutter-bar will also be held rigid when the clutches 91, 92 are released.

The connections between the bar 40 and the cutting tool constitute an overhanging arm when the cutter is parallel to the floor and adjacent thereto. It often occurs in coal mines that the entries are narrow and therefore it may be desirable to produce a sumping cut with the cutter substantially at the floor while the overhanging arm supports the cutter bar so that the rear end thereof will be between the mine wall or rib and the ends of the ties of the track. In this narrow space the cutter may be located and adjusted to extend forward for a rectilinear cut in continuation of the lateral walls of the entry. Thus a kerf may be made, the lower surface of which will be in continuation of the floor on which the track is laid and the kerf cut will have its lower surface below the upper surface of the rails of the mine track. Such kerfs may be cut on both 130 sides of the mine track and connected by a kerf in advance thereof, thus completing a continuous kerf extending across the area in front of the mine track. By means of the screw 12 the cutter bar may be elevated sufficiently to 140 clear the rails of the mine track during transportation.

It should also be noted that by applying power to the wheel 17 after positioning the kerf-cutter at the floor, a kerf may be cut in advance of 150

the truck through an arc of 180° on a radius extending from the center of the turntable to the outer end of the cutter-bar. Such a radius may be still further increased by extending outwardly the rack bar 40 and holding it locked in adjusted position by the worm gearing 46, 47 shown in Fig. 1. Very wide entries of varying widths may thus be advanced by mining operations including kerf-cutting followed by shooting down the coal in the usual manner leaving straight ribs on both sides of the entry. In making all such arcuate cuts through 180° the full effective length of the cutter-bar is employed.

It is also important to note that in advancing all entries of relatively narrow widths, the full effective length of the cutter-bar is used and consequently a rapid advance of the entries is always maintained. This may be understood by reference to Fig. 14 considered as a plan view. When advancing entries of intermediate widths, the turntable mechanism may be employed to secure the arcuate feed between the rectilinear sumping and withdrawal cuts, but when relatively narrow entries are to be advanced, it is preferred to adjust the bar 40 to a longitudinally central position and rely on the feed of the cutter on the axis 81 or 81' to secure the arcuate cuts. Whenever the cutter-bar is fed rectilinearly, either for sumping or withdrawing, it is locked at an acute angle. Then when the chain cutter is fed into the face of the mine vein, it is presented edgewise to the coal and projected into the latter to its full depth which is taken advantage of in making the arcuate cut. Therefore, for all arcuate cuts, whether the kerf-cutter is fed through 180° for the widest entries or is fed arcuately through lesser angles between the rectilinear cuts, the arcuate feed is obtained while the kerf-cutter is extended into the coal to its full effective length. The distance the entry is advanced by blasting after each cut is therefore substantially the same for the entries of various widths from the widest to the narrowest and for all entries the rib cuts as illustrated at X^1 and X^2 in Fig. 14 are along straight lines to facilitate the production of straight walls at the sides of the entries.

While the foregoing refers to mining operations to extend entries in advance of the truck or in advance of the mine track, the method illustrated in Figs. 17 to 24 inclusive, is used in a longwall system of mining, the upright or shearing cuts X being made as illustrated in Fig. 14. By swinging the cutter-bar toward or from the axial line of the neck it may be positioned for the making of the slanting kerfs X^3 and $X^{3'}$ and the cutter may be fed rectilinearly by increments by sliding the sub-frame 21 along the main frame D while the end of the rope is anchored at 35 and the truck is jacked in stationary position on the mine track. It should be observed that the rope 36 may be anchored to the truck frame 8 for this operation, and therefore when the frame 21 is fed along the frame D, the machine is entirely self-contained. The machine is also entirely self-contained when operating to produce kerfs in advance of the truck and in advance of the mine track as above explained.

The kerfs X^3 and $X^{3'}$ along the mine wall may also be produced by moving the whole machine along the mine track after the position of the kerf-cutter has been adjusted by swinging the same toward or from the axial line of the neck.

In view of the foregoing explanation it is ob-

vious that the great flexibility of the machine illustrated enables a single kerf-cutter to perform arcwall operations at the floor, at the roof and intermediate the floor and roof by producing horizontal kerfs; also arcwall operations in upright or shearing positions; and furthermore, the same machine may be used to carry out either longwall operations or breast operations to rapidly advance entries of varying widths while the full length of the cutter is always employed for the arcwall feeding movements.

By referring to Fig. 1 it will be seen that the axis of the turntable is permanently vertical and when the kerf-cutter is parallel to the horizontal axis of the bearing 52 the axis 81, which is the pivot of the cutter bar within the orbit of the cutter chain, is spaced from the turntable axis so as to be located at all times outside of the boundaries of the truck and turntable. By means of the wheel 60 the axis 81 is adjustable between vertically and horizontally extending positions, while the cutter is being supported in all adjusted positions. Variable spacing of the axis 81 from the turntable axis is effected by movement of the rack bar 40.

When the truck is anchored to the mine track or blocked against movement along the same the kerf-cutter while occupying a horizontal plane may be swung on the turntable axis or on the axis 81. Separate means are provided for this purpose. The inclination of the kerf-cutter may be adjusted by the wheel 67 and the elevation by means of the screw 12. The distance of the axis 81 from the turntable axis may be varied by shifting the rack bar 40. When the kerf-cutter is thus adjusted it will be locked against turning on the axis 81 by the self-locking worm gearing 95, 96; it will be locked against movement transversely of its own plane by the worm gearing 63, 64; it will be locked against turning on the horizontal axis of the bearing 52 by the worm gearing 56, 57; and it will be locked against rectilinear movement relatively to the truck by the worm gearing 46, 47. By applying power to the wheel 17 the kerf-cutter may be fed along an arc on a radius which may be much longer than the length of the cutter bar. Therefore, as above explained, the machine may be operated in very wide entries or rooms as well as relatively narrow entries or rooms, and, moreover, the working face by reason of the long radius of the cut will more nearly approach a straight face.

While the truck is anchored to the mine track the rope winding mechanism comprising the rope 36 may be used to slide the frame 19 along the track D' , D'' to secure a rectilinear cut in a plane parallel to the mine track, such plane being either horizontal as shown in Fig. 24 at $X^{1'}$, or inclined upwardly or downwardly as shown at X^3 and $X^{3'}$ in Figs. 18, 20 and 22, or vertical with the cutter bar spaced back from a longwall face or projecting into the roof or projecting into the floor at any adjusted distance from the mine track. Such rectilinear feeding movement with the kerf-cutter in adjusted position will be effected by self-contained power-operated mechanism when the rope 36 has its free end anchored to the truck 8, the turntable 10 or the frame D. It should be understood that such rectilinear feeding movement may be effected at either side of the mine track, and also in advance thereof transversely of the mine track, and during such rectilinear feed-

ing movement the axis 62 remains parallel to the track D', D² but may be above or below the horizontal axis of the bearing 52 with the kerf-cutter in any one of many different planes comprising horizontal planes at the roof and floor and intermediate inclined planes as well as horizontal planes adjacent the axis 52 one above the same and one below the same.

While the truck is anchored to the mine track or while the frame D is anchored by means of roof jacks the kerf-cutter may be fed rectilinearly either transversely of the mine track or parallel thereto provided the kerf-cutter is in a plane parallel to the axis 52 or to the path of travel of the rack bar 40. In the form shown in Figs. 1 and 2 the motor F may be operated to drive the cutter chain while the motor 22 effects rectilinear feeding movement. The feed may therefore be controlled in accordance with the hardness of the material being cut while the speed of travel of the cutter chain may be maintained independently of the feed. In the form shown in Figs. 1 and 2 the cutter-chain driving motor reciprocates rectilinearly with the rack bar 40 while in the form shown in Figs. 8 and 9 the cutter chain is operated by means extending along the axis of the supporting bearing 52.

In the form shown in Figs. 1 and 2 a complete mining machine comprising the motor F, cutter bar A, and mechanism for operating the same including arcuate feed of the kerf-cutter in its own plane, is suspended from the overhanging support E. It can readily be seen that when the kerf-cutter is swung to a horizontal plane at the roof of the mine chamber from the dotted line position shown in Fig. 1 the track mounted apparatus will be operable to cut kerfs in planes well above a plane extending horizontally through the top of the machine. The overall height of the framework may therefore be lower than the maximum height of the coal vein. The same machine may also cut horizontal kerfs between the top of the frame D and the horizontal axis of the bearing 52 by tipping the motor upside down from the position shown in Fig. 1 and turning the cutter bar 180° from its full line position. Whether the kerf-cutter is near the axis 52, above it or below it, or whether it is at the roof or at the floor, it may be adjusted in elevation rectilinearly by means of the screw 12.

The inclination of the cutter bar may at any time be adjusted on the axis 62 along arcuate lines transverse of the cutter bar; the cutter bar may also at any time be adjusted on the axis 52 to vary the inclination of the cutter bar relative to a longitudinal center line thereof. Consequently, the telescoping guiding mechanism shown in Figs. 1 and 1^a will be useful to prevent tilting of the frame D relative to the truck, the screw 12 will effect rectilinear adjustment in elevation and the gears 15 and 16 will always be kept properly in mesh with each other. After the cutter bar has been adjusted to a desired position it will be locked at the turntable by the worm gearing 15, 16, at the rack bar by the worm gearing 46, 47, at the neck E' by the worm gearing 56, 57, at the axis 62 by the worm gearing 63, 64, and at the casing of the motor F by the worm gearing 95, 96. The frame 19 may be locked against one end or the other of the frame D relative to the track D', D² by means of the worm gearing 29, 33, when the free end of the rope 36 is anchored to the frame D or the truck 8.

While it is preferred to carry out the method illustrated in Figs. 23 and 24 by longwall operations for the horizontal kerfs and by the operation illustrated in Fig. 14 for the upright slanting kerfs it should be understood that the kerfs illustrated in Figs. 23 and 24 may also be cut in the coal face in advance of the mine track. Spaced-apart horizontal kerfs X¹⁹ may be cut as above described. The upright slanting kerfs X²⁰ may be cut by adjusting the axis 62 in an upright position parallel to the kerf X²⁰ to be cut. By means of adjustments effected by means of the worm gearing 63, 64 and 15, 16 the kerf cutter may be located in various parallel positions each in planes parallel to the slant of the axis 62. By means of the rope-winding mechanism rectilinear feed may be effected by moving the whole machine along the mine track. Sumping and withdrawal rectilinear feeding movements may be connected by arcuate feeding movements on the axis 81 thus in each instance cutting a parallel ribbed kerf in a slanting plane as illustrated at X²⁰ in Fig. 23. The range of operations on the coal face extending across the space in advance of the mine track may be increased by inverting the axis 62 when the cutter is located on the opposite side of the mine track from that shown in Fig. 1. The upright slanting kerfs X²⁰ may therefore be located in parallel spaced-apart positions and extended over a wide area from the position adjacent one rib of the entry to a position adjacent the other rib thereof. It will thus be seen that in addition to the longwall operations hereinbefore described in connection with Figs. 23 and 24, shortwall operations may also be carried out in the manner just described.

Having thus fully disclosed an embodiment of the invention, what is desired to be secured by Letters Patent is:

1. The method of mining coal which consists in cutting spaced apart elongated parallel kerfs in the face of the mine vein by longwall operations, and producing upright spaced-apart slanting kerfs to facilitate the dislodgement of large blocks of coal.

2. The method of mining coal which consists in cutting parallel spaced-apart kerfs in the face of the mine vein, one at the roof, one at the floor, and one intermediate the floor and roof, and producing upright spaced-apart slanting kerfs inclined rearwardly from the roof toward the floor to facilitate the dislodgment of large blocks of coal.

3. The method of mining which consists in producing spaced-apart kerfs in the face of a mine wall by longwall operations, and producing upright spaced-apart slanting kerfs to facilitate the dislodgement of large blocks of coal.

4. The method of mining coal which consists in cutting parallel spaced-apart kerfs in the face of the mine vein including a kerf at the roof and a kerf at the floor, and producing slanting kerfs in the coal vein to facilitate the dislodgement of large blocks of coal.

5. The method of mining which consists in cutting a plurality of elongated kerfs in the face of the mine vein by longwall operations, and producing upright slanting spaced-apart kerfs in such face to facilitate the dislodgement of large blocks of material.

6. The method of mining which consists in cutting a plurality of elongated kerfs in the face of the mine vein by longwall operations, and producing upright slanting spaced-apart kerfs in the

cut face at right angles thereto to facilitate dislodgment of large blocks of material.

7. The method of mining which consists in cutting a plurality of elongated kerfs in the face 5 of the mine vein by longwall operations at various elevations, and producing upright slanting spaced-apart kerfs in such cut face in planes at right angles thereto to facilitate the dislodgment of large blocks of material.

10. 8. The method of mining which consists in cutting a plurality of spaced-apart horizontal kerfs in a mine vein, and cutting a plurality of upright spaced-apart kerfs in upright planes each slanting relative to the vertical, the cutting 15 of each of the upright kerfs being formed in three steps, the first being a cut into the face of the mine vein rectilinearly effected, the second being a cut transversely effected in the same

plane, and the third being a withdrawal cut reversely and rectilinearly effected to complete a parallel ribbed kerf in such slanting plane.

9. The method of mining which consists in cutting a horizontal plane kerf in the plane of the roof of the mine chamber, cutting a horizontal plane kerf in the plane of the floor of the mine chamber, cutting an elongated plane kerf along the face of the mine vein intermediate the floor and the roof, cutting upright spaced-apart plane kerfs intersecting the aforesaid kerfs, each of said upright kerfs being slanting relative to the vertical, and dislodging the kerf-cut material.
